UNITED STATES PATENT OFFICE.

WARREN C. EVANS, OF EXETER, NEW HAMPSHIRE, AND HENRY D. ALLARD, OF BRADFORD, AND JOHN B. KENISON, OF LYNN, MASSACHUSETTS.

SOLE-EDGE-BLACKING MACHINE.

SPECIFICATION forming part of Letters Patent No. 629,126, dated July 18, 1899.

Application filed May 4, 1897. Serial No. 635,010. (No model.)

To all whom it may concern:

Be it known, that we, WARREN C. EVANS, of Exeter, county of Rockingham, State of New Hampshire, and HENRY D. ALLARD, of Bradford, and JOHN B. KENISON, of Lynn, county of Essex, State of Massachusetts, have invented an Improvement in Sole-Edge-Blacking Machines, of which the following description, in connection with the accompanying drawings, is a specification, like letters and numerals on the drawings representing like parts.

This invention has for its object the production of a novel, convenient, and highly-efficient apparatus for applying blacking or other coloring-matter to the edges of boot and shoe soles and heels rapidly and accurately with an even coating of any desired density.

Means are provided to absolutely prevent the "coloring-matter," which term as herein used includes blacking, from touching the upper or the top of the sole when desired, as in "fair-stitch" work, the coloring-matter being applied without spattering by a rotary transerrer, against which the work is held, and the arrangement of the mechanism is such that the coloring-matter can be applied to the sole edge only or to the edge and top, as may be desired.

We have also made provision for scouring or smoothing the sole edge just before the color is applied thereto, so that as the operator moves the work the color is applied to that portion thereof which has been just before smoothed, so that subsequent rubbing down is obviated.

In the course of our experiments to improve apparatus of this class so that the coloring-matter shall be applied in a smooth, continuous, and uniform layer or coat we have discovered that the best results are attained by the use of a rotatable applying device having a continuous preferably slightly-yielding non-metallic periphery, to which the coloring-matter is supplied, and thereby transferred to the work.

Various other novel and useful features will be hereinafter described, and particularly pointed out in the following claims.

Figure 1 in front elevation represents an apparatus embodying our invention for ap-

plying coloring-matter to boots and shoes as will be described. Fig. 2 is a vertical sectional view thereof on the line $x-x$, Fig. 1, looking to the right. Fig. 3 is a rear elevation of the apparatus. Fig. 4 is a like view, enlarged, taken through the main or driving shaft and a portion of one of the reservoirs for the coloring-matter, showing also in section the guard or shield and the intermediate controlling devices between the reservoir and the color-transferrer. Fig. 5 is an inner side view of the clutch mechanism on the driving-shaft shown at the right, Fig. 1. Fig. 6 is a vertical sectional view taken through the longitudinal axis of the main or driving shaft, showing a portion of the clutch mechanism. Fig. 7 is a partial vertical sectional view of the mechanism shown in Fig. 4, on the line x' looking to the left, with the color-transferrer omitted. Fig. 8 is a detail elevation showing the device for scouring or smoothing the edge of the sole and in connection with the color-applying mechanism.

Referring to Fig. 1, the main frame A, of suitable shape to support the working parts of the apparatus, is preferably mounted on a shelf or stand A', said frame having an upright A², which provides a bearing a for the main driving-shaft B, the latter having a second bearing a' . A gear C is fast on the shaft B adjacent the inner end of the bearing a' , and at the other end of the said bearing abuts the sleeve-like hub b of a clutch member B', fast on the shaft. The other or loose clutch member is shown as a cone-pulley B², rotatably mounted on the hub b and retained in place by a collar b³, fast on the main shaft, said clutch member having its inner face concaved or dished, as clearly shown in Fig. 6. A dog b² (see dotted lines, Fig. 5) is secured to the outer end of a stud b', mounted to rock in the clutch member B', said dog at times engaging a stop b³, secured on the inner or concave face of the clutch member B², while on the inner side of the member B' a trigger b⁴ is rigidly secured to the stud b'. A spring s normally holds the trigger in the position shown in Fig. 5, with the dog b² in engagement with the stop b³, the lip of the trigger projecting beyond the periphery of the clutch member B'.

A rock-shaft b^5 , Figs. 1, 2, 3, and 5, is mounted on the main frame and in the standard A^2 , a set-screw 5 adjustably securing on the rock-shaft an arm b^6 , on which is mounted a headed spring-controlled stud b^7 , normally held in the path of movement of the lip of the trigger by a suitable spring S, (partially shown in Fig. 5,) the tripping of the trigger disengaging the dog and stop b^8 , and so disconnecting the clutch members when the lip of the trigger engages the headed stud b^7 , the rotation of the clutch being in the direction of the arrow 75, Fig. 5. As shown in said Fig. 5, the trigger b^4 is supposed to have just engaged the stud b^7 , and slight further rotation of the clutch will tip the trigger to move the dog b^2 out of engagement with the stop b^8 . By making the trigger double, as shown, its inner end engages the hub of the clutch member B' when tipped inward to thereby prevent undue movement of the trigger.

An actuating-arm b^8 , (see Figs. 1 and 2,) fast on the rock-shaft b^5 , is adapted to be moved by the operator to rock the shaft b^5 in the direction of the arrow 70, Fig. 5, against the spring S, to thereby withdraw the clutch-controller stud b^7 from engagement with the trigger, so that the clutch will be thrown into operation and the main shaft rotated. The arm b^6 has laterally projecting from its inner face a lug b^9 , adapted to be engaged by a shoulder b^{10} on a lever b^{12} , pivoted on the frame at b^{13} , so that when the actuating-arm b^8 is depressed to support the apparatus the shoulder b^{10} will engage the lug b^9 , and thereby maintain the clutch in operative position until the operator, by lifting the lever b^{12} , releases the lug, permitting thereby the rock-shaft b^5 to return to normal position and through the clutch-controlling stud b^7 engage the trigger and, as described, effect the disengagement of the two clutch members.

The main shaft has secured thereon (see Figs. 1, 3, and 4) separated collars 7 8, to receive between them an arm c , mounted to rock on the preferably-enlarged portion B^3 of the main shaft, said arm at its rear end having a bearing c' , through which is extended a shaft c^2 , on the outer end of which is secured a suitable scouring or smoothing roll c^x , having a roughened periphery and, as shown best in Fig. 3, slightly conical in shape. At its inner end the shaft c^2 has fast thereon a suitable pulley c^3 , to which rotation may be transmitted by a belt (not shown) from any suitable source of power to rotate the scouring-roll c^x in the direction of the arrow 65, Fig. 8. A bracket c^4 on the standard A^2 is threaded to receive an exteriorly-threaded sleeve c^5 , provided with a suitable check-nut c^6 , the upper end of the sleeve being located below the rear end of the arm c , as clearly shown in Fig. 8. A spring S' is attached at one end to said arm and at its other end to a rod c^7 , extended loosely through the lower end of the sleeve c^5 and threaded to receive thereon an adjusting-nut

c^8 , by which the tension of the spring may be regulated. It will be seen that the scouring-roll is thus supported to rock bodily by and at the rear of the main shaft, the spring holding it in a yielding manner against the sleeve, the latter being adjusted in its bracket to suit different shapes of shoes and to coöperate properly with the color-transferrer, to be hereinafter described.

The spring S' can be adjusted independent of the sleeve, and the adjustment of the sleeve will also, if desired, affect tension of the spring.

The color-transferrer is herein shown as an annulus T, having a continuous non-metallic and slightly-yielding periphery, and up to the present time we have obtained the best results with a rubber transferrer or one having a rubber periphery, as the color will thereby be applied to the work smoothly and evenly without streaking or spattering.

We prefer to give a slightly-conical form in an outward direction to the periphery of the transferrer, to thereby secure the more perfect distribution of the color over the work, the edge of the sole being held by the operator against the transferrer as it is rotated, the latter being applied, as shown in Fig. 4, to the enlarged portion B^3 of the main shaft and abutting against the collar 8.

The edge of the sole from the shank portion forwardly around the toe is preferably scoured, while it is unnecessary to scour the shank portion, and we have shown our apparatus as provided with two transmitters T T', the former only operating in conjunction with a scouring-roll, so that the shoe will be first applied to the transmitter T, the color being applied as the operator draws the shoe toward him, the rotation of the scouring-roll being such that any dust from the sole is thrown away from the transmitter, and afterward the sides and fore part of the sole edge are colored, and the shoe is then applied to the transmitter T', which colors the shank. This arrangement, however, is largely a matter of convenience to the operator, as one machine can thus do the work of two separate ones, while it will also be obvious that the scouring-roll can be thrown out of operation at times, if it is desired to use one and the same color-transmitter for both the shank and fore part of the sole. The transmitter T' is mounted on a shaft B^4 , held in suitable bearings on the frame and having fast thereon a gear B^5 , which meshes with an intermediate gear B^6 in mesh with gear C, fast on the main shaft, so that the two transmitters are rotated in the same direction. Each transmitter has its own reservoir for the "coloring material," which term includes blacking, and as the reservoirs and their operative parts are counterparts one of the other only one will be described in detail, the reference-letters D d d' of the one corresponding, respectively, to the letters E e e' of the other.

The main frame A has on its front and rear

sides lugs $A^{16} A^{17}$ to receive the shanks of yokes $a^{16} a^{17}$ to embrace the upper ends of the reservoirs D E, respectively.

The reservoir D (see Fig. 4) is open at its lower end and receives therein an upturned annular flange d , formed on the bottom plate D', which bottom plate is provided with a lateral extension D², provided with a boss d' , through which is extended a screw-bolt d^2 , 5 the latter fitting into a horizontal notch d^x in a part of the standard A², while a thumb-nut d^3 at the opposite end of the screw-bolt acts to clamp the extension D² firmly to the framework of the apparatus. The reservoir is secured to its bottom plate in any suitable manner, either by soldering or by a ground joint 15 to hold in the color without leakage. The bottom is slotted at d^4 above the transfer T, said slot serving as an outlet for the contents of the reservoir, while a valve, shown as a rod d^5 , is adapted to move longitudinally in the reservoir-bottom, the inner end of the rod passing through an ear d^6 on the under side 20 of the extension D², longitudinal movement of the valve opening more or less the outlet, a spring s' , connected at one end to the ear d^6 and at its other end to a pin d^7 on the rod, normally retracting the latter to open the outlet d^4 . The pin d^7 is adapted to be engaged when 25 desired by a gravity-latch d^8 , pivoted on the exterior of the extension at d^9 (see Fig. 1) to hold the valve in such position as to close the outlet, as would be the case when the machine is not in use.

30 The coloring-matter does not pass directly from the outlet d^4 onto the transfer, but onto a small distributing-roll f, pivotally mounted in rocking supports f', fulcrumed at f^2 in the downturned flange of a block f^x, 35 attached to the under side of the bottom plate D', the outer ends of the supports f' being nicked to receive the annular heads of suitable adjusting-screws f³, threaded into the block f^x, so that rotation of the said screws will 40 raise or lower the distributing-roll f to press 45 more or less tightly upon the transfer.

It is found in practice that the interposition of the distributor between the reservoir-outlet and the transfer greatly assists in the 50 smooth and even distribution of the ink upon the transfer, and also prevents spattering.

A piston-rod or plunger d¹⁰, vertically movable through the upper closed end D^x of the reservoir, has a head or piston d¹² secured thereto to enter loosely the reservoir and at 55 its inner stroke to fit quite snugly within the flange d, while when the plunger is lifted its head d¹² will be raised above the flange, so that a portion of the material in the reservoir can pass beneath the head to be positively expelled through the outlet d⁴ when the plunger is next depressed.

A slide-rod m^x, vertically movable in bearings 22 33 of the main frame, has attached 60 thereto arms m m', which engage the two plungers d¹⁰ and e¹⁰, between collars 3 4 thereon, respectively, to effect the reciprocation of

the plungers, the slide-rod being depressed by a spring S⁵ and elevated by engagement with one arm m² of a bell-crank lever pivoted 70 on the main frame at m³, the other arm m⁴ of said lever being located in the path of and to be engaged by a cam-lug B⁸ on the inner side of the gear B⁵, as clearly shown in Fig. 1, whereby the plungers will be elevated and depressed once for every complete revolution of the transmitters.

We have provided means for automatically closing the reservoir-outlets when the machine is stopped, so that the coloring-matter 80 will not at such time flow, and for this purpose an inclined shaft h is mounted to rock in bearings in brackets 30 and 31 on the main frame and standard A², respectively, said shaft being provided at its lower end with a toe h' in the path of and to be engaged by a tappet h², fast on the horizontal controlling-shaft b⁵, the tappet engaging, as best shown in Fig. 2, an adjusting-screw h³ in the toe. At its upper end the rock-shaft has adjustably secured thereto an arm h⁴, extended forwardly to bear against the valve-rod e⁵, as shown in Fig. 3, when the parts are in the positions shown in Figs. 1, 2, and 3. A sleeve h⁵ is loosely mounted on the shaft h, between 95 the inner end of the toe h' and the collar h^x, fast on the shaft, said sleeve being provided with a forwardly-extended arm h⁶, adapted to bear against the exposed end of the valve-rod d⁵ when the machine is not in use. The sleeve h⁵ has a toe h⁷ at its lower end, provided with an adjustable stud h⁸, to be engaged by a tappet h⁹, fast on the controller-shaft b⁵. Now when the machine is at rest the two tappets on the controller rock-shaft b⁵ will act on 100 the coöperating toes of the rock-shaft h and sleeve h⁵ to turn the arms h⁴ and h⁶ to the left, Fig. 1, forcing the valve-rod to nearly close the reservoir-exits, so that the flow of coloring-matter will be greatly diminished, it being 110 sufficient to partially shut off the flow when the operator removes one boot or shoe and is about to present another one to the color-transfer. If, as has been described, the coloring-matter is entirely shut off, as when 115 the machine is left for the day or for any length of time, the operator will grasp the extensions h¹⁰ h¹¹ of the arms h⁴ h⁶, respectively, pushing them to the left until each valve-rod is caught by its gravity-detent d⁸ or e⁸.

Movement of the valve-rods to the right, Fig. 1, is limited by threaded studs d⁵⁰ e⁵⁰, mounted in the main frame and adapted to impinge against the arms h⁴ h⁶, respectively.

Of course a greater quantity of the coloring-matter must be delivered when it is thick than when it is thin, and in the former case the valve-rods are permitted to be opened more than they would be in the latter case by means of the limiting or stop studs d⁵⁰ e⁵⁰.

Inasmuch as the coloring-matter will not be thrown or spattered from the transfer hereinbefore described, a shield is unnecessary; but it is necessary to provide a guard

to protect the upper, and we provide such guard and at the same time effect the application of the coloring-matter to the top of the sole.

5 The bottom of each reservoir is provided with a standard, one being shown in section at d^{20} , Fig. 4, interiorly threaded at its lower end to receive a stop-screw d^{21} , through which is extended a vertically-movable shank d^{22} , the upper end of which is received in a longitudinal hole d^{23} of the standard, the upper end of the hole being threaded to receive an adjusting-screw d^{24} . The inner end of said screw is shown as bearing on a flange d^{25} , which rests upon the top of a spring s^8 , the lower end of which is seated in the recessed upper end of the shank d^{22} , and by adjusting the screw d^{24} the tension of the spring is varied. A thin guard-plate d^{26} is secured to the lower end of the foot d^{22} , adjacent the outer end of the transerrer T, said guard-plate having a curved lower end provided with a groove d^{27} in the edge thereof, and a bent-wire guide d^{28} , extending below the guard-plate, is secured at its ends to the sides of the guard-plate d^{26} . The coloring-matter flows from the transerrer onto the inner face of the guard-plate and flows down the wire guide d^{28} , which when in use enters between the upper and the sole, the coloring-matter flowing from the guide onto the top of the sole, while the edge of the latter has color applied thereto by the transerrer T.

35 The coloring-matter is prevented from passing under the lower edge of the guard-plate and onto the shoe by the groove d^{27} , in which the coloring-matter collects and drops onto the wire guide d^{28} , which thus serves not only to apply the coloring-matter to the top of the sole when desired, but it also furnishes a guide for the operator in manipulating the shoe, such manipulation being assisted by a bottom gage, shown as a truck n on a stud n' , extended out from the standard A².

45 The shank d^{22} is provided with a pin 45, Fig. 4, which rests on the top of the stop-screw d^{21} , and by adjusting the latter the extreme lower position of the guard-plate and guide is provided for.

50 To prevent any accidental loosening of the stop-screw, a clamping-screw 46 is extended through the body of the standard d^{20} to bear against the stop-screw d^{21} and prevent its rotation.

55 The guard-plate is held in parallelism with the outer end of the transerrer T by means of depending ears d^{29} , bearing on the outer face of the guard-plate d^{26} .

60 The guard is used for all plain work and about the shanks of boot and shoe soles; but with fair-stitch work it is necessary to protect not only the upper, but also the stitching at the top of the sole, and in doing such work the transerrer is moved slightly away from and out of contact with the guard-plate, so that no coloring-matter will pass thereto from the said transerrer, and in Figs. 1 and

2 the color-transerrer T is shown as moved slightly to the right for this purpose.

65 The movement of the transerrer is readily effected by adjustment of the collar 90 on the shaft B⁴. The operator holds the boot or shoe in his hands, with the bottom of the sole against the bottom gage n and with the edge of the guide d^{28} in the crease between the sole 75 and the upper, and the edge of the sole is pressed up against the edge of the rotating transerrer, this upward movement of the shoe and guide being permitted by the yielding support for the guide, and the transerrer applies the blacking or coloring-matter evenly 80 and rapidly to the sole edge as it is turned to present new portions thereto, the guard-plate protecting the upper effectually. The movement of the boot or shoe is toward the operator, so that when the scouring-roll is used 85 the sole edge is scoured just before it is moved into contact with the color-transerrer. The operation will be precisely the same in fair-stitch work, with the exception that, as has 90 been described, the guard and color-transerrer would be slightly separated to prevent the passage of color from one to the other.

95 With some kinds of coloring-matter or stain it is desirable to maintain it heated when the apparatus is in use, and for that purpose we have provided burners P and P', (best shown in Fig. 3,) located beneath the reservoirs D and E, respectively, on branch pipes p p' , leading from a common pipe p^x , which may 100 be connected with any suitable gas-supply.

In the claims we have herein used the term "coloring apparatus" generically, said term including blacking or other coloring-matter or stain which is to be applied to the edge or 105 upper portion of a boot or shoe sole.

In this application we do not claim in a sole-edge-blacking apparatus a rotatable brush against which the sole edge is held with an adjacent reservoir provided with a discharge-opening to deliver its contents directly upon the brush, means to positively force the contents of the reservoir through the opening, and an automatically-controlled valve for such opening, as they form the subject-matter 115 of a claim in another application, Serial No. 681,502, renewed May 23, 1898, by two of the inventors herein named, the color-applying device in the present invention consisting of a rotatable member having a continuous 120 yielding periphery as opposed to a brush the periphery of which is formed of a multitude of independent bristles.

Having fully described our invention, what we claim, and desire to secure by Letters Patent, is—

1. In an apparatus of the class described, a rotatable color-transerrer, having a continuous yielding rubber periphery and against which the edge of the sole to be colored is 130 held, a color-distributer, a reservoir adjacent the transerrer and having a discharge-outlet delivering the coloring-matter directly to said distributer, a controlling-valve for the outlet,

and means to automatically operate the said valve, substantially as described.

2. In an apparatus of the class described, a rotatable color-transferrer having a yielding continuous periphery and against which the edge of the sole to be colored is held, a reservoir adjacent the transferrer and having a discharge-outlet, a controlling-valve for said outlet, a distributer-roll between the outlet and the transferrer and contacting with the latter, to distribute coloring-matter thereto, and means for positively adjusting the distributer-roll to and from the transferrer to regulate the distribution of coloring-matter to the transferrer, substantially as described.

3. In an apparatus of the class described, a rotatable color-transferrer against which the edge of the sole to be colored is held, a reservoir, a color-distributer between the transferrer and reservoir, the latter being provided with a discharge-outlet, a valve for said outlet, and means to normally open the valve, combined with actuating devices, including a clutch, to rotate the color-transferrer, a clutch-controller, and means intermediate said controller and valve, to automatically close the latter when the clutch is released, substantially as described.

4. In an apparatus of the class described, a reservoir having a discharge-outlet for its contents, means to agitate the contents of the reservoir, a valve separate from said means to open and close the outlet, a detent to maintain the valve closed, and an adjustable stop to regulate the extent of movement of the valve to open the outlet, substantially as described.

5. In an apparatus of the class described, a rotatable color-transferrer having a continuous periphery and against which the edge of the sole to be colored is held, a yielding-supported upper guard and guide adjacent the outer end of the transferrer, said guide having a groove in its lower edge next the transferrer, and means to rotate the transferrer, substantially as described.

6. In an apparatus of the class described, a rotatable transferrer having a continuous periphery and against which the edge of the sole to be colored is held, a guard-plate mounted adjacent the end of the transferrer and having a groove in its lower edge, and a loop-like guide extended below the grooved edge of the guard-plate, to enter the crease between the sole and upper of a boot or shoe, substantially as described.

7. In an apparatus of the class described, a rotatable shaft, having a yielding continuously-coherent periphery mounted thereon, a yielding-supported upper-guard adapted to

contact with the outer end of and receive color from the transferrer, a guide on the lower portion of the guard, to enter the crease between the sole and upper of a boot or shoe, said guard also being provided with means for conveying color to the top of the sole without spattering, and means to adjust the upper-guard, substantially as described.

8. In an apparatus of the class described, a plurality of color-transferrers having each a continuous periphery, a reservoir for each transferrer, means to positively distribute the contents onto the transferrers, an upper-guard located at the end and mounted independently of each transferrer, one transferrer being mounted ahead of the other in position to enable the operator quickly to shift a shoe from one to the other as desired, and means to rotate the transferrers, substantially as described.

9. In an apparatus of the class described, a main shaft, a clutch one member of which is secured to the shaft, a manually-operated clutch-controller, and a color-transferrer mounted on the shaft, combined with a reservoir adjacent the transferrer and having a discharge-outlet, a spring-opened valve for the outlet, and means operated by movement of the clutch-controller to release the clutch, to partially close the valve, substantially as described.

10. In an apparatus of the class described, a rotatable color-transferrer against which the edge of the sole to be colored is held, a scouring-roll located at the rear of the transferrer, means to rotate the scouring-roll in the same direction as the transferrer, and a reservoir to supply color to the transferrer, substantially as described.

11. In an apparatus of the class described, a rotatable color-transferrer, a rocking carrier, a scouring-roll mounted thereon at the rear of the transferrer, and means to rotate the scouring-roll in the same direction as the transferrer, combined with a spring to normally depress the scouring-roll, and an adjustable stop to limit the downward movement of the roll, substantially as described.

In testimony whereof we have signed our names to this specification in the presence of two subscribing witnesses.
